(57) **CLAIM**

The ornamental design for a placemat having a napkin and chopsticks holder, as shown and described.

DESCRIPTION

FIG. 1 is a perspective view of a first embodiment of a placemat having a napkin and chopsticks holder in a position of use with a napkin and chopsticks package in accordance with my design;

FIG. 2 is a front view of the first embodiment;

FIG. 3 is a rear view of the first embodiment;

FIG. 4 is a right side view of the first embodiment;

FIG. 5 is a left side view of the first embodiment;
FIG. 6 is a top view of the first embodiment;
FIG. 7 is a bottom view of the first embodiment;
FIG. 8 is a perspective view of a second embodiment of a placemat having a napkin and chopsticks holder in a position of use with a napkin and chopsticks package;
FIG. 9 is a front view of the second embodiment;
FIG. 10 is a rear view of the second embodiment;
FIG. 11 is a right side view of the second embodiment;
FIG. 12 is a left side view of the second embodiment;
FIG. 13 is a top view of the second embodiment;
FIG. 14 is a bottom view of the second embodiment;
FIG. 15 is a perspective view of a third embodiment of a placemat having a napkin and chopsticks holder, torn in two places and in a position of use with a napkin and chopsticks package;
FIG. 16 is a front view of the third embodiment;
FIG. 17 is a rear view of the third embodiment;
FIG. 18 is a right side view of the third embodiment;
FIG. 19 is a left side view of the third embodiment;
FIG. 20 is a top view of the third embodiment;
FIG. 21 is a bottom view of the third embodiment;
FIG. 22 is a perspective view of a fourth embodiment of a placemat having a napkin and chopsticks holder, torn in two places and in a position of use with a napkin and chopsticks package;
FIG. 23 is a front view of the fourth embodiment;
FIG. 24 is a rear view of the fourth embodiment;
FIG. 25 is a right side view of the fourth embodiment;
FIG. 26 is a left side view of the fourth embodiment;
FIG. 27 is a top view of the fourth embodiment; and,
FIG. 28 is a bottom view of the fourth embodiment.
The broken line showing of a napkin and chopsticks package illustrates environment only and forms no part of the claimed design. The broken line showing of the perimeter of the placemat and the tears in FIGS. 15 and 22 form no part of the claimed design.
